WATER SKIING TOW ROPE RETRACTOR

Robert S. Kay, 4358 N. Queen Ave.,
Minneapolis, Minn. 55412

Filed Apr. 21, 1966, Ser. No. 1,974

Term of patent 7 years

(Cl. D71—1)

FIGURE 1 is an elevational view taken from the top of a water skiing tow rope retractor;

FIGURE 2 is a front end elevational view of the same;

FIGURE 3 is a rear end elevational view of the same;

FIGURE 4 is a right end elevational view of the same;

FIGURE 5 is a left end elevational view of the same; and

FIGURE 6 is a bottom view of the same.

The rope and handle shown in broken line in FIGURE 1 is for illustrative purposes only.

I claim:

The ornamental design for a water skiing tow rope retractor, as shown and described.
